UNITED STATES PATENT OFFICE

KENNETH J. TOBIN AND CARL E. EKLIND, OF CHICAGO, ILLINOIS, ASSIGNEES TO
CAMEL COMPANY, OF CHICAGO, ILLINOIS, A CORPORATION OF ILLINOIS

CAR-DOOR TRACK

Application filed February 16, 1928. Serial No. 254,681.

This invention relates to a car door track, and it is among the objects of this invention to prevent seepage between the track and car to facilitate the flow of rain and slush from the track and to cause the door to gravitate outwardly to more effectively clear the side of the car when the same is opened or closed.

The invention comprises the novel structure and combination of parts hereinafter described and more particularly pointed out and defined in the appended claim.

In the accompanying drawings, which illustrate a preferred embodiment of this invention and in which similar reference numerals refer to similar features in the different views:

Figure 1 is a fragmentary sectional view through a house car illustrating a track involving this invention with a door support thereon.

Figure 2 is a fragmentary rear elevational view of the track in detached form.

Figure 3 is a sectional view of a slightly modified form of track in connection with its attaching means.

Figure 4 is a view similar to Figure 3 illustrating a further modified form of track.

Figure 5 is a view similar to Figure 3 illustrating a further modified form of track.

Figure 6 is a sectional view of a bottom track.

In the drawings, several forms of tracks are illustrated, all of which embody the invention. Each of the tracks has an attaching flange 1 which is adapted to be attached to some supporting means upon the car such as the flange 7 of a Z-bar. The edges of such flange may also be peened over, as indicated at 3, to provide calking edges. Each attaching flange has a horizontal ledge or flange 4 which slightly inclines downwardly in an outward direction. The rollers 5 of a sliding door 6 are adapted to travel upon the flange 4 which forms the track proper. The inclined feature of the track flange 4 has a two-fold purpose. In the first place, it more readily sheds the rain and snow, and in the second place, it causes the rollers 5 to gravitate towards the outer edge of the track flange with the result that the door will travel clear of the side of

the car during its opening and closing movements.

Provision is made for a sealing substance 7 such as plaster, cement, between the track and its support. In the present instance, this provision is illustrated as in the form of grooves or scorings 2 longitudinally directed. The plastic cement in said grooves, which is pressed tightly against the attaching flange 7, in assembly, provides a tight joint that effectively excludes the rain and weather, so that water or moisture cannot seep therethrough.

We are aware that many changes may be made, and numerous details of construction may be varied through a wide range without departing from the principles of this invention and we therefore do not purpose limiting the patent granted hereon, otherwise than necessitated by the prior art.

We claim as our invention:

The combination with a vertical flange, of a track member having a roller traveling portion and a vertical attaching flange secured to said vertical flange, said attaching flange having a peened upper edge and a longitudinal groove adjacent said vertical flange and a sealing substance in said groove.

In testimony whereof, we have hereunto subscribed our names.

CARL E. EKLIND.
KENNETH J. TOBIN.
